UNITED STATES PATENT OFFICE.

EDWIN JOHN PAYNE GALLWEY, OF WEYMOUTH, ENGLAND.

COIN-FREED APPARATUS FOR DELIVERING STAMPS, &c.

SPECIFICATION forming part of Letters Patent No. 601,852, dated April 5, 1898.

Application filed October 5, 1897. Serial No. 654,135. (No model.)

To all whom it may concern:

Be it known that I, EDWIN JOHN PAYNE GALLWEY, a subject of the Queen of Great Britain, residing at Weymouth, England, have 5 invented a new and useful Improved Coin-Freed Apparatus for Delivering Stamps and other Articles, of which the following is a specification.

This invention relates to coin-freed apparatus for delivering stamps, railway and other tickets, checks, and other articles, the said apparatus being, however, chiefly designed to be employed for the delivery of postage-stamps.

According to my invention I provide a suitable casing, within which I arrange a band or ribbon of suitable material and designed to hold in pockets or the like the stamps or other articles to be delivered on the insertion of a 15 coin into the apparatus. The band or ribbon is so arranged that it can be fed forward intermittently on the insertion into the apparatus of coins proper to the same and present a stamp or other article before an opening or 20 orifice in the casing, all as hereinafter more particularly described.

In the accompanying drawings, Figure 1 is a front elevation of a suitable arrangement of apparatus made according to my invention 25 and designed to deliver postage-stamps. Fig. 2 is a sectional elevation thereof, the section being on the line 2 2, Fig. 1. Fig. 3 is a front sectional elevation of the apparatus, and Fig. 4 is a sectional plan thereof. Fig. 5 is a section on the line 5 5, Fig. 1, drawn to a larger 30 scale. Fig. 6 is an elevation, drawn to a larger scale, of a portion of the band or ribbon. Fig. 7 is a vertical transverse section thereof. Fig. 8 is a plan of an arrangement of the apparatus with modified band-operating mechanism. Fig. 9 is a detail thereof. Fig. 10 is a section, drawn to a larger scale, through an arrangement of band and delivery-openings which I sometimes employ. Fig. 11 is a plan 35 thereof without the band. Fig. 12 is an elevation of a portion of this form of band.

Referring to Figs. 1 to 7, *a* is the casing of the apparatus, the said casing having a partition which divides the till *b* from the portion 40 containing the mechanism.

c is the band or ribbon, the construction of which is hereinafter described.

d is a let-off cylinder or roller upon which the band *c* is initially wound, and *e* is a take-up cylinder or roller upon which the said band is intermittently wound on the insertion of coins into the apparatus. Both these cylinders are pivotally supported by a bracket or frame *f*, screwed to the bottom of the casing *a*, as shown in Figs. 3 and 4.

The cylinder or roller *e* is provided with a coiled spring *e'*, which is normally kept wound up, so that the said roller constantly tends to unwind the ribbon or band *c* from the roller *d* and wind it upon itself. The movement of 55 the spring-roller *e* is controlled by means of an escapement device consisting of a ratchet *g* upon the roller and a double pawl or let-off device *h*, pivoted at *h'* to the frame *f* and provided with an outwardly-extending arm *i*, operated by the coin, as hereinafter described. The number of teeth on the ratchet *g* will correspond to the number of pockets contained in a length of ribbon *c* equal to the circumference of the spring-roller *e*, so that a to- 60 and-fro movement of the arm or extension *i* of the pawl *h* allows the spring-roller *e* to move through the distance of one tooth, thereby causing a length of band or ribbon *c* equal to the width of a pocket containing a stamp 65 or other article to be unwound from the roller *d*. The band *c* is guided by a strip *j*, so as to pass in front of an orifice or window *k* in the apparatus, whereby the stamps or other articles held upon the face of the said band 70 are successively presented in front of the window or orifice *k* on the insertion of successive coins into the apparatus and can be easily removed from the band or ribbon, as hereinafter described.

The coin-chute consists of a passage *l* of the exact width of the coins proper to the machine and of the same height and breadth as the said coins and so inclined that it conducts the coins inserted into it to the money-till *b*, 75 provided in the apparatus. The hereinbefore-described extension or arm *i* of the double pawl or let-off device *h* normally extends into the coin-chute through a slot *l'* therein, as shown in Figs. 2, 3, and 4, so as to block 80 the passage of the coin *m*, which when inserted into the chute *l* drops onto the said extension or arm *i*. To free the coin *m* and operate the mechanism, I provide a pusher *n*, 85

having an external knob or button *o*, the said pusher working in a slot *l*² in the coin-chute *l* and being normally held in its uppermost position by a spring *p*. The pusher *n* is so arranged that on the knob or button *o* being depressed by the purchaser the said pusher *n* descends upon the upper end of the coin *m* and thereby pushes the extension or arm *i* of the pawl *h* out of the way of the said coin, thereby releasing the pawl *h* from the tooth of the roller-ratchet *g*, with which it is in engagement, so as to allow the roller *e* to rotate through half a tooth and the coin *m* to drop into the till *b*. A spring *q* in connection with the pawl or let-off device *h* immediately returns the arm *i* of the same to its normal position, thereby releasing the ratchet *g* another half-tooth, so that during the operation the ribbon *c* is unwound from the roller *d* onto the roller *e* a length of the band *c* equal to the space of one tooth—that is to say, a length corresponding to the width of a pocket containing a stamp or other article, which is therefore brought in front of the window or orifice *k* in the front of the apparatus and can be removed by the purchaser.

In practice I find it advantageous to employ the following means for securing the stamps *c'* to the band or ribbon *c*, it being essential that the said stamps shall be easily removable from the band or ribbon when exposed in the window of the apparatus: The band or ribbon *c* is folded over at its lower edge and the two contiguous parts are stitched together at distances apart slightly exceeding the width of the stamps, which are then inserted in the divisions or pockets *c*² thus formed in the lower half of the band.

The pockets *c*² are numbered in rotation, the first pocket on the band—that is to say, the pocket last brought before the window or orifice *k* of the apparatus—having the word "Empty" written upon it and the successive pockets being numbered "1," "2," "3," "4," &c., so that when a pocket has been brought in front of a window and the stamp *c'* removed therefrom the number on the pocket indicates the number of stamps still remaining on the band *c*. When the last stamp appears before the window, its pocket bears the word "Empty," as above described, so that intending purchasers will be made aware that no more stamps can be obtained from the apparatus until it is refilled. The lower half of the orifice *k* is covered by a glass plate *r'* and the upper half thereof is covered by a spring plate or tongue *r*, fixed to one side of the orifice and pressing with its free end against the band, so as to prevent the latter from being tampered with. A slit *r*² is formed between the adjacent edges of the glass plate *r'* and the spring-plate *r*, through which the upper half of the stamps extend and through which they may be withdrawn, as hereinafter described.

To enable the stamps *c'* to be easily removed from the pockets, I provide the spring

plate or tongue *r* with a small inclined projection *s*, so that as the band is moved forward on the insertion of the coin in the apparatus, as hereinbefore described, the spring-tongue *r* gets behind the advancing stamp *c'*, the upper part of which is then tilted outward as it slides onto the inclined projection *s*, as indicated in Fig. 5, so that the stamp can be easily removed from the pocket by the purchaser, the stamps being withdrawn through the slit *r*², formed between the edges of the plates *r* and *r'*.

t is a spring fitted to the bracket or frame *f* and the arms of which bear upon the cylinder or roller *d* for preventing the said roller and band from moving too easily, and the case of the apparatus is arranged so that it can be quickly and easily refilled—for instance, the front may be hinged and arranged to drop when the top is removed.

Although I have described the band as being wound intermittently onto a spring-roller, which is the arrangement I have found to answer well in practice, it will be obvious that the intermittent movement of the roller can be effected positively on the insertion of the coin.

In the arrangement of my apparatus illustrated in Figs. 8 and 9 the band *c* instead of being wound on a let-off roller is folded upon itself and stored in a receptacle *u*. This receptacle *u* is provided with an orifice *u'* for the band *c*, having guide-rollers *u*² *u*³, between which the said band passes. The receptacle contains a sliding back *u*³, which is pressed against the rear part of the folded band *c*, so as to hold the said band taut. The take-up cylinder or roller *e* is in this case shown arranged to be operated positively by the pusher and coin. To this end the hereinbefore-mentioned spring *e'* is dispensed with and the ratchet *g* is actuated by a lever *v*, pivoted at *v'* and having a rearwardly-extending arm *v*², upon which the coin drops when inserted into the apparatus. The front end of the lever *v* is jointed at *v*³ in such a manner that when it is pushed by the action of the coin *m*, in the manner hereinbefore described, into the position shown in dotted lines in Fig. 8 it is held rigid, so as to move the roller *e* in the direction indicated by the arrow *x* and feed forward the band *c* through a distance corresponding to one tooth of the ratchet *g*. The lever *v* is, as soon as the coin *m* has passed the arm *v*², pulled back to its initial position by the spring *w*, the joint *v*³ enabling it to pass the ratchet *g*. To hold the cylinder or roller in the positions into which it is intermittently moved on the insertion of the coins, I provide a spring-catch *y*, Fig. 9, which engages with recesses *y'* in the roller, the number of the said recesses *y'* corresponding to that of the teeth of the ratchet *g*.

The band *c* instead of being folded as hereinbefore described and as illustrated in Figs. 1 to 7 can be folded along the center line, as shown in Figs. 10 and 12, so that the stamps (or

other articles) project above the band. In the construction of the delivery-orifice and guide *j* (illustrated in Figs. 10 and 11) the upper part of the guide is rabbeted and the band *c* passes through the channel formed by the glazed lower part of the orifice *k* and the front of the guide *j*. The said channel is of such a height that the band *c* is completely inclosed therein, the stamp *c'* projecting through the slit *j'* at the upper end thereof, as clearly shown in Fig. 10. By this means the spring-tongue *r* is rendered unnecessary, as access cannot be had to the band through the orifice *k*.

15 It is clear that my apparatus can be provided with more than one ribbon, coin-chute, and set of rollers. It can, for instance, be arranged to deliver stamps of different values.

Having now particularly described and ascertained the nature of my said invention and in what manner the same is to be performed, I declare that what I claim is—

20 1. In a vending-machine the combination with the band provided with a series of transverse pockets, each provided with an indicating device, means for feeding said band, a casing provided with a delivery-aperture in line with the path of said band, a transparent plate closing a portion of said aperture and 25 adapted to lie over the indicating devices of said band, and a plate extending over the adjacent portion of said aperture, said plates having a slit formed between them in line with the path of the band to allow the articles carried by said band to project therethrough, substantially as described.

25 2. In a vending-machine, the combination with the band provided with a series of transverse pockets of feeding mechanism for said

band, a casing provided with a delivery-aperture in the path of said band, a pair of plates extending over portions of said aperture and inclosing said band, said plates having their adjacent edges separated to form a slit in line with the path of the band, to allow 40 the articles carried by the band to project therethrough, substantially as described.

3. In a vending-machine, the combination with the band provided with a series of transverse pockets opening toward one edge of the band, feeding mechanism for said band, a casing provided with a delivery-aperture in the path of the band and a spring plate or tongue in said aperture for covering the exposed portion of the band, and provided with an inclined projection adapted to pass between the band and the articles carried thereby, substantially as described.

4. In coin-free apparatus for delivering stamps and other articles the combination with a casing having a window or orifice, of a band for holding the stamps or other articles, of two rollers upon one of which the band is initially wound and upon the other of which the said band is intermittently wound upon 60 the insertion of coins into the apparatus so as to bring the stamps upon the band successively in front of the window or orifice, and of a spring plate or tongue for covering the exposed portion of the band, and having an 65 inclined projection for tilting forward the stamps or other articles in the window or orifice, substantially as described.

EDWIN JOHN PAYNE GALLWEY.
